UNITED STATES PATENT OFFICE.

THOMAS J. CHRISTY, OF ST. LOUIS, MISSOURI.

GAS-GENERATOR.

No. 866,713.

Specification of Letters Patent.

Patented Sept. 24, 1907.

Application filed March 12, 1907. Serial No. 362,012.

To all whom it may concern:

Be it known that I, THOMAS J. CHRISTY, a citizen of the United States, residing in the city of St. Louis and State of Missouri, have invented new and useful Improvements in Gas-Generators, of which the following is a specification.

This invention relates to gas generators designed for producing a gas suitable for lighting and heating purposes, such as that created by the action of water on carbid that has been previously immersed in a petroleum oil and the invention embodies in its organization a water-receiving tank or vessel containing a generator over which is arranged a movable bell in which the generated gas is stored for delivery to the outlet pipe or duct, there being carried by said bell an inlet or feed tube through which the carbid is deposited into the generator.

The invention has for its objects to provide a comparatively simple, inexpensive device of this character wherein the generated gas will be thoroughly washed before passing into the bell, one in which the latter will move smoothly and evenly under the action of the generated gas, one wherein the generator and tank may be conveniently cleaned when circumstances require, and one in which the feed tube, which normally securely closed, may be readily opened to permit introduction of the carbid.

With these and other objects in view, the invention comprises the novel features of construction and combination of parts, more fully hereinafter described.

In the accompanying drawings, Figure 1 is a vertical section taken centrally and longitudinally through a gas apparatus embodying the invention. Fig. 2 is a horizontal section taken on the line 2—2 of Fig. 1. Fig. 3 is a similar view taken on the line 3—3 of Fig. 1. Fig. 4 is a view similar to Fig. 1, showing the parts in a different position.

Referring to the drawings, 1 designates a main vessel or tank from which arises a pair of fixed guide-rods or standards 2 and adapted in practice to be partly filled with water or other suitable liquid 3, there being entered into the tank 1 at a point adjacent its bottom, an outlet pipe or duct 4 having communication with the house or service pipe and adapted to open within the tank at a point above the normal level of the liquid 3, while connected in the wall of the tank near its bottom is a discharge spigot 5 through which the water may be drawn off from the tank. Arranged in the vessel 1 is a receptacle 6 constituting a generating chamber provided at its lower end with a tubular portion or duct 7 leading outward through the wall of the tank 1 and closed at its outer end by means of a cap 8 normally held in closed position by a cam lever 9 pivoted in a yoke 10, in turn pivoted to the duct, it being noted in this connection that the bottom 11 of the generator in-

clines downwardly toward the tubular discharge portion 7. The upper end of the receptacle 6 is closed by a cover 12 provided with depending gas escape tubes 13 communicating at their upper ends with the interior of the generator through ports 14 and constituting passages for a purpose which will presently appear, there being formed on the cover 12 a depending guide-tube 15 which projects downwardly into and below the surface level of the liquid 3 within the tank.

Disposed in the tank 1 over the pipe 4 and generator 6 is a movable hood or bell 16 to which is fixed a pair of guide arms 17 provided at their upper ends with suitable eyes to receive the rods 2, there being formed in the walls of the bell, which projects downward into and is sealed by the liquid 3, a pair of vent openings 18 for a purpose which will hereinafter appear, while fixedly attached to the top wall of the bell is a depending feed tube 19 slidably disposed in and for movement through the guide tube 15. The bell is weighted at 20 and provided through its cover with a valve-controlled relief nozzle 21, while the tube 19 is closed at its upper end by means of a cap 22 normally fixed in closed position by a locking member in the form of a cam-lever 23, the lower end of the tube being normally closed by a conical closure valve 24 carried by a rod or stem 25 having at its upper end a cross-head 26 adapted to engage flanges 27 for holding the valve in closed position.

In practice, the tank is suitably filled with water, as shown, and the cap 22 removed after first releasing the lever 23, so that a quantity of petroleum oil can be introduced into the tube 19 in which the oil rests on the surface of the water, in accordance with the well known laws of gravitation. A charge of carbid is next dropped into the tube 19 and finally fed into the generator 6 by releasing and permitting the valve 24 to drop open, it being noted in this connection that on introduction into the generator, the carbid passes through and becomes saturated with the oil, which is essential to and usual in the production of the particular gas desired, and further that after the carbid has been deposited in the generator, the valve 24 is closed as is also the cap 22. The carbid is, under the action of the water, generated in the ordinary manner into gas which passes through the ports 14 into the passages 13, being carried by the latter below the surface of the water through which it arises into the bell 16 and finally passes off through the duct 4 to the service pipe or pipes. It will be understood that the generator may, by removing the cap 8, be readily cleaned and that the cleaning operation is facilitated owing to the bottom 11 of the receptacle being inclined downwardly toward the discharge tube 7. The bell 16, which will rise under the influence of the gas, moves downward under the action of the weight 20, thereby forcing the gas under pressure outward through the pipe 4, and in the event of the bell rising 110

to abnormal height, the gas will escape through the vent openings 18, thus to relieve the pressure within the bell.

Having thus described the invention, what I claim is:-

1. In a device of the class described, a tank adapted to be partially filled with liquid, a receptacle sustained in the tank and having a gas escape tube extended downward below the normal level of the liquid, said receptacle being provided with a cover having a depending guide-tube, a movable bell arranged in the tank and carrying a feed tube extended downward through said guide tube, a gas discharge pipe leading from the tank and opening within the latter at a point above the level of the liquid, means for guiding the bell in its movements, means for closing the feed tube, and a valve for controlling communication between the feed tube and receptacle.

2. In a device of the class described, a tank adapted to receive a quantity of liquid, a generating receptacle sustained in the tank and provided with a discharge tube opening outside of the latter, said receptacle having an inclined bottom leading downward to the discharge tube, a cover for the receptacle provided with a depending guide-tube, a movable bell arranged in the tank and having a feed tube slidably disposed in the said guide-tube, means for closing the feed tube, a gas duct leading from the generator to a point below the surface level of the liquid in the tank, and a discharge pipe leading from the tank and opening within the latter at a point above the surface level of the liquid.

In testimony whereof, I affix my signature in presence of two witnesses.

THOMAS J. CHRISTY.
